COLLAPSIBLE TUBE CAP

Albert Goss, Dunedin, Fla.

Application April 26, 1934, Serial No. 722,559

6 Claims. (Cl. 221—60)

This invention relates to a cap to control the dispensing and closing of a collapsible tube, such as is used for paste materials of various kinds.

It is particularly aimed to provide a novel construction which is operable through a turning movement of the cap and which employs, in combination with the cap proper and the discharge nozzle or neck of the tube, a plurality of plates having cam means to control their opening and closing and also the pressure thereof against the nozzle.

The more specific objects and advantages will become apparent from a consideration of the description following taken in connection with accompanying drawing illustrating an operative embodiment.

In said drawing:—

Figure 1 is a view in elevation of a collapsible tube embodying the invention,

Figure 2 is a plan view of the cap,

Figure 3 is a cross sectional view taken on the line 3—3 of Figure 1,

Figure 4 is a view similar to Figure 3, but showing the plates in open position,

Figure 5 is a vertical sectional view taken on the line 5—5 of Figure 2,

Figure 6 is a vertical sectional view taken on the line 6—6 of Figure 2,

Figure 7 is a detail section taken on the line 7—7 of Figure 2,

Figure 8 is an inverted plan view of the cap proper, and

Figure 9 illustrates the plates in plan and in edge view.

Referring specifically to the drawing, 10 designates a conventional collapsible tube, made of lead, lead alloy or other soft metal, adapted to be rolled through the turning of a key at 11, to dispense the contents of the tube through a discharge opening 12, usually rectangular in cross section, and contained within a neck or nozzle 13, preferably having an outwardly extending marginal flange 14.

Surmounting the nozzle or neck 13 and rotatable thereon is a cap member 15 which has its lower surface resting on the nozzle, and below which depends an integral attaching flange 16, which is bent inwardly at 17 to overlap the lower edge of flange 14 and thus rotatably mount the cap against accidental displacement. The cap 15 has a discharge opening at 18, preferably rectangular and adapted in discharge position to register with the opening at 12.

The discharge is governed by the position of two substantially semicircular disks or plates at

19 which are adapted to be moved away from each other with their diametral edges always remaining in parallelism and to be moved toward each other for closing and also to be moved tightly against the upper surface of the nozzle 13 for better closing. To this end the upper surface of nozzle 14 is provided with ribs 20 at a right angle to opening 12 and on opposite sides thereof. Said ribs 20 are slidably engaged in grooves 21 in the under surfaces of the plates 19. In addition, plates 19 on their upper surfaces have lugs 22 which are engaged in cam slots 23 of the cap member 15.

Said plates 19 are disposed in a recess in the under surface of the cap 15 and about the recess, and cams 24 are provided to engage the edges of the plates 19 in their closed position, to apply more effective closing pressure thereon. In addition, the upper walls in the grooves 23 have cams at 25 which bear on the lugs 22 in the closed position of the disks to press them downwardly against the upper surface of the nozzle to more effectively close the tube.

Midway between the cams 24, and diametrically opposite each other are stop pins 26.

In the operation of the device, the cap 15 is turned to open position, to the extent permitted by engagement of cams 24 with pins 26, in which position, the openings 12, 18 and space caused by separation of plates 19 alone so that the paste may be squeezed or dispensed from the tube upon winding of the stem 11. The cap has a polygonal flange 27 to facilitate engagement and turning. It will be clear that when the cap is turned, the plates 19 slide relatively to each other along the ribs 21, caused by the coaction of the cam grooves 23 and the lugs 22. In the closed position, the diametral edges of the plates 19 are forced into more effective engagement by the coaction of the cams 24 with the peripheral edges of the plates and such plates are also brought more tightly against the upper edge of the nozzle 13 by the engagement of the cams 25 against the upper edge of the lugs 22.

Various changes may be resorted to provided they fall within the spirit and scope of the invention.

I claim as my invention:—

1. In combination with a discharge nozzle having a discharge opening therethrough, a cap having a discharge opening therethrough rotatably mounted on the nozzle, a pair of substantially segmental plates disposed between the cap and nozzle and adapted to move relatively to one another to collectively close and expose said

opening, and means to simultaneously move said plates through the turning movement of the cap to control the discharge through said opening and between the plates.

5 2. In combination with a discharge nozzle having a discharge opening therethrough, a cap having a discharge opening therethrough rotatably mounted on the nozzle, a pair of substantially segmental plates disposed between the cap and nozzle and adapted to move relatively to one another to collectively close and expose said opening, and means to simultaneously move said plates through the turning movement of the cap to control the discharge through said opening and between the plates, said nozzle having a flange thereon and said cap having a flange overlapping the first mentioned flange to mount the cap on the nozzle.

10 3. In combination with a discharge nozzle having a discharge opening therethrough, a cap having a discharge opening therethrough and cam grooves therein, said cap rotatably mounted on the nozzle, a pair of substantially segmental plates disposed between the cap and nozzle and adapted to move relatively to one another to collectively close and expose said opening, and means to simultaneously move said plates through the turning movement of the cap to control the discharge through said opening and between the plates, said means comprising lugs on said plates

15 4. In combination with a discharge nozzle having a discharge opening therethrough, a cap having a discharge opening therethrough and cam grooves therein, said cap being rotatably mounted on the nozzle, substantially segmental plates disposed between the cap and nozzle, means to move said plates relatively through the turning movement of the cap to control the discharge through said opening and between the plates, said means comprising lugs on said plates engag-

ing in said cam grooves, and ribs on the nozzle engaging grooves in the plates to guide the plates in their sliding movement.

5 5. In combination with a discharge nozzle having a discharge opening therethrough, a cap having a discharge opening therethrough and cam grooves therein, said cap being rotatably mounted on the nozzle, substantially segmental plates disposed between the cap and nozzle, means to move said plates relatively through the turning movement of the cap to control the discharge through said opening and between the plates, said means comprising lugs on said plates 10 15 engaging in said cam grooves, ribs on the nozzle engaging grooves in the plates to guide the plates in their sliding movement, cam means in said grooves to engage the lugs to urge the plates tightly against the nozzle in closed position, and cam means engaging the periphery of the plates to urge them into contact in closed position. 20

6. In combination with a discharge nozzle having a discharge opening therethrough, a cap having a discharge opening therethrough and cam grooves therein, said cap being rotatably mounted on the nozzle, substantially segmental plates 25 30 35 disposed between the cap and nozzle, means to move said plates relatively through the turning movement of the cap to control the discharge through said opening and between the plates, said means comprising lugs on said plates engaging in said cam grooves, ribs on the nozzle engaging grooves in the plates to guide the plates in their sliding movement, cam means in said grooves to engage the lugs to urge the plates tightly against the nozzle in closed position, cam 35 means engaging the periphery of the plates to urge them into contact in closed position, said nozzle and cap having overlapping flanges to secure the cap in place and the cap having a recess housing said plates. 40
